UNITED STATES PATENT OFFICE.

ARTHUR C. NELSON, OF DULUTH, MINNESOTA.

AUTOMATIC STOKER.

1,138,501.

Specification of Letters Patent.

Patented May 4, 1915.

Application filed December 30, 1913. Serial No. 809,655.

To all whom it may concern:

Be it known that I, ARTHUR C. NELSON, a citizen of the United States, residing at Duluth, in the county of St. Louis and State of Minnesota, have invented new and useful Improvements in Automatic Stokers, of which the following is a specification.

The invention relates to fuel feeders or stokers and more particularly to the class of coal feeder mechanism for boats, locomotives or the like.

The primary object of the invention is the provision of a stoker wherein the fuel will be automatically fed to the fire box of an engine thereby avoiding the hand shoveling of the coal thereto by a fireman as is usual.

Another object of the invention is the provision of a stoker wherein the fuel will be prevented from choking the hopper or feed pipe so that the feeding of the fuel will not be interrupted during the working of the stoker, or while being actuated from the steam in the engine.

A further object of the invention is the provision of a stoker of this character which is simple in construction, reliable, positive and efficient in its operation and inexpensive in manufacture as well as the running thereof.

With these and other objects in view the invention consists in the construction, combination and arrangement of parts as will be hereinafter more fully described, illustrated in the accompanying drawings forming a part of this specification and pointed out in the claims hereunto appended.

In the drawings: Figure 1 is a vertical longitudinal sectional view through the stoker constructed in accordance with the invention showing a portion of the fire box of the engine. Fig. 2 is a sectional view on the line 2—2 of Fig. 1. Fig. 3 is a vertical transverse sectional view on the line 3—3 of Fig. 1. Fig. 4 is a side elevation of the stoker.

Similar reference characters indicate corresponding parts throughout the several views in the drawings.

Referring to the drawings in detail A designates a portion of the fire box of an engine the said box being of the ordinary and well known construction for containing the fuel to be burnt. Arranged at one side of the fire box A is a feed cylinder B in which is arranged a piston cylinder C the latter being

provided with the usual steam chest D having therein a slide valve arrangement to control the feed of steam to either side of a piston E to reciprocate it within the cylinder C. This cylinder C is located at one end of the feed cylinder B while the opposite end of the latter communicates with the fire box A and connected to the piston E is a piston rod F on the outer end of which is mounted a shovel head G integrally formed with a tube form hood H which is adapted to telescope over the piston cylinder C, the head G and hood H being designed to work forwardly and backwardly within the cylinder B for a purpose presently described.

Swingingly connected to the end of the cylinder B at its point of communication with the fire box A is a drop door I while formed on the head G is a finger or projection J which serves to open the door I on the advancement of the head G in the direction of the fire box so that fuel delivered into the cylinder B will be admitted into the fire box for the coaling of the engine.

Communicating with the cylinder B at the top thereof is a forwardly inclined feed hopper K into which is adapted to be delivered coal in any suitable manner. At the discharge end of the hopper K is arranged a swinging door L which is closed on the advancement of the head G toward the fire box while on the reverse movement of the head G the door L will automatically drop to open position thereby admitting coal from the hopper K into the cylinder B for the subsequent delivery thereof to the fire box.

Suitably journaled exteriorly on the opposite walls of the hopper K are spaced shafts M to which are fixed sprocket wheels N having trained thereover endless chains O, the walls of the hopper K being cut away to permit the chains to travel interiorly and exteriorly thereof. Each of these chains O has one-half stretch thereof provided with fingers P while connected to a pair of shafts M are sprocket wheels Q over which is trained an endless chain R the latter being adapted to operate the chains O in unison, so that one stretch thereof the teeth P will work within the hopper K for positively feeding the fuel from the hopper into the cylinder B, the disposition of the teeth P on the chains O being such as to travel within the hopper K at the time only when the door L is open and on the closing of the door the other stretchers of the chain O devoid of

the teeth P will travel interiorly of the hopper K thereby becoming ineffective for the feeding of the fuel from the hopper K into the cylinder B.

- 5 One of the shafts M has suitable connection with any desirable type of motor for the driving of the chains O to agitate the fuel within the hopper so as to avoid the choking of the hopper and thereby interrupting the feeding of the fuel to the fire box.

From the foregoing it is thought that the construction and operation of the invention will be clearly understood and therefore a 15 more extended explanation has been omitted.

It is to be understood that the valve in the steam chest can be regulated so that at one time the stoker will throw the coal 20 way into the fire box and at another time not so far, thereby assuring an even fire. Furthermore, the stoker and feeding mechanism are regulated by the motors so that they will work in respective order, that is to say, when the stoker is passive the feeding 25 mechanism will be at a standstill, and the motor that starts the stoker should be operative when the motor is active for operating the feeding mechanism.

What is claimed is—

- 30 1. A stoker comprising a delivery cylinder adapted for communication with a fire box, a door hinged to the cylinder for normally closing communication between it and the fire box, a feed pipe inclined toward the fire 35 box and communicating with the cylinder at the top thereof, a hinged door supported internally of the cylinder for closing communication between the feed pipe and the same and normally gravitated to open position, a 40 piston cylinder of a diameter less than the internal diameter of the delivery cylinder and fixed centrally interiorly of the same, a hollow head slidably telescoped upon the 45 delivery cylinder for movement longitudinally

thereof, a piston working within the piston cylinder and connected directly to the hollow head, means for supplying and exhausting fluid to and from the said piston cylinder for actuating the piston therein, and a 50 curved nose formed on the head and projected therefrom for raising the second-named door and subsequently opening the first-named door on movement of the head in one direction.

55 2. A stoker comprising a delivery cylinder adapted for communication with a fire box, a door hinged to the cylinder for normally closing communication between it and the fire box, a feed pipe inclined toward the fire 60 box and communicating with the cylinder at the top thereof, a hinged door supported internally of the cylinder for closing communication between the feed pipe and the same and normally gravitated to open position, a 65 piston cylinder of a diameter less than the internal diameter of the delivery cylinder and fixed centrally interiorly of the same, a hollow head slidably telescoped upon the piston cylinder and working within the delivery cylinder for movement longitudinally thereof, a piston working within the piston cylinder and connected directly to the hollow head, means for supplying and exhausting 70 fluid to and from the said piston cylinder for actuating the piston therein, a curved nose formed on the head and projected therefrom for raising the second-named door and subsequently opening the first-named door on movement of the head 75 in one direction, and means within the feed pipe for positively feeding fuel therefrom to the first-named cylinder.

76 In testimony whereof I affix my signature in presence of two witnesses.

ARTHUR C. NELSON.
